UNITED STATES PATENT OFFICE.

PHILIPPE DE CLAMECY, OF BOSTON, MASSACHUSETTS, ASSIGNOR TO CORONA TYPE-WRITER COMPANY, INC., A CORPORATION OF NEW YORK.

TYPE-WRITING MACHINE.

1,278,871.

Specification of Letters Patent. Patented Sept. 17, 1918.

Application filed March 4, 1916. Serial No. 82,138.

To all whom it may concern:

Be it known that I, PHILIPPE DE CLAMECY, a citizen of the United States, and a resident of Boston, county of Suffolk, and State of 5 Massachusetts, have invented certain new and useful Improvements in Type-Writing Machines, of which the following is a full, clear, and exact description.

This invention relates more particularly 10 to a foldable front strike or other visible typewriting machine.

One of the principal objects of the invention is to provide a typewriting machine in which the platen carriage and its direct support may be folded rearwardly and downwardly within the main frame or main frame part of the machine and the keyboard folded upwardly and inwardly also within the main frame or main frame part thus containing substantially the entire mechanism 20 within the main frame part of the machine in order that the working parts may be protected as well as the machine made compact and convenient for transportation purposes.

Another object of the invention is to provide a typewriting machine in which key-operated levers comprising two parts may be both mounted upon a common rod or axis and so constructed as to form a knuckle or 25 knee-joint in order that one part of each key-operated lever may fold with respect to the other part without disconnecting the parts.

Other objects of the invention are to provide a keyboard frame part which is foldable 35 upwardly with a part of the key-operated levers and means whereby the foldable parts of the key-operated levers may be locked and held to said keyboard frame part; to provide 40 a machine wherein upwardly and rearwardly moving type-bars are employed and which type-bars are actuated by relatively foldable parts of key-operated levers; to provide simple means as an escapement mechanism for typewriting machines; to provide simple operating mechanism for imparting a lengthwise step-by-step feed to a ribbon; to provide means whereby ribbon spools may be frictionally held; to provide a 45 ribbon holder which may move to and from the platen and which when the platen is 50

given a compact movement is adapted to fold automatically to a compact position; to provide simple means for releasing the escapement to adapt the carriage to move 55 freely along the carriage bed; and to provide simple and efficient line-spacing mechanism for the platen.

A further object of the invention is to provide simple and efficient mechanism for 60 shifting the platen and carriage to adapt the type-bars to have a plurality of type or characters thereon.

A still further object of the invention is to provide means whereby the ribbon feed and 65 the escapement mechanism may be simultaneously operated by the universal bar.

Another object of the invention is to provide a typewriter in which the type basket and type-bars may be moved bodily from a 70 normal operative position to a more compact one.

A still further object of the invention is to provide a machine which is simple in construction, which may be readily made and 75 assembled, and which when compact provides a substantially uniform package.

With these and other objects in view, the invention will be hereinafter more particularly described with reference to the accompanying drawings, which form a part of this application, and will then be pointed out in the claims at the end of the description.

In the drawings, Figure 1 is a front elevation of one form of machine embodying the 85 invention.

Fig. 2 is a longitudinal section, partly in elevation, of the machine.

Fig. 3 is a plan view partly broken away.

Fig. 4 is a fragmentary view, partly 90 broken away and partly in section, showing a part of the means for operating the escapement and the ribbon feed mechanism.

Fig. 5 is an enlarged fragmentary side elevation of a part of the escapement operating mechanism.

Fig. 6 is a side elevation of a part of the escapement actuating means shown in Fig. 5.

Fig. 7 is a fragmentary enlarged view showing one kind of joint for the two parts 100 of the key-operated levers to adapt both parts in one position to operate in unison.

and to permit relative folding between said parts.

Fig. 8 is an enlarged section, partly in elevation, of means for holding the platen carriage support in its normal operative position; and

Fig. 9 is a view similar to Fig. 2, partly diagrammatic, showing a construction wherein the type basket and type-bars may be moved from a normal operative position to a compact one below the upper surface of the main frame or main frame part.

The main frame or main frame part 10 has upright corner pillars or posts 11 with the usual rubber tips or feet 12 and connecting the posts at the lower portion thereof is a base 13. At the upper portion of the main frame part is a top plate or member 14 and there may be side plates if desired, it being understood that the frame, or main frame part, may be of the usual or of any preferred construction. At the forward portion of the machine is a keyboard frame part 15. This keyboard frame part 15 is hinged at 16 to the main frame part and at the outer portion thereof may be provided with rubber feet of the usual kind. The keyboard frame part is tray-like in form and is adapted to fold upwardly and inwardly as shown in dotted lines in Fig. 2. The hinge or pivot 16 is in the form of bolts located on opposite sides of the main frame part in alinement, and said bolts have threaded stems which are engaged by thumb nuts 17 which assist in holding the keyboard frame part in its folded and in its normal operative position. This keyboard frame part 15 at its inner portion is provided with an abutting surface 18 which is adapted to engage a substantially L-shaped spring 19 secured to the frame base 13 so as to position and hold said frame part in a normally horizontal position, and in the folded position of said frame part the latter is retained in such position by means of a spring 20, one end of which is secured to the under surface of the frame part 13 or otherwise held as desired, the thumb nuts 17 serving as additional holding means for said frame part.

A keyboard 21 is mounted to move with the keyboard frame part 15. This keyboard may be of a universal or standard kind and comprises keys 22 which are arranged in banks or groups and are mounted upon the upper ends of vertical portions of levers 23. The levers 23 are each formed in two parts 24 and 25. The parts 24 and 25 are in alinement when in a normal operative position and all of the parts of said levers are pivotally held to a transversely extending rod 26. The rod 26 is held in a main frame part of the machine between the forward corner posts 11 of the main frame part or in any other desired way. The parts 25 of the key-

operated levers extend horizontally and are 65 in alinement with the horizontal portions of the parts 24, and on one of said parts, as the part 24 of each lever, is a shoulder 27 which is adapted to engage a shoulder 28 of the part 25 when in normal operative position 70 as shown in Fig. 2, so that on the depression of one of the keys 22 the inner end of the part 25 of the two-part lever on which the key is mounted will be forced upwardly. Each lever 23 is restored from a depressed 75 position to its normal operative position by a spring 29, one end of which is secured to the base 13 and the other end passed through an aperture in the key lever part 25. The shoulders 27 and 28 and the mountings of 80 the parts 24 and 25 provide a knee or knuckle joint which adapts all of the parts 24 of all of the key-operated levers to fold relatively to the parts 25 as shown in dotted lines in Fig. 2. 85

The inner ends of the parts 25 of the key-operated levers 23 have a pin 30 and each pin is adapted to move in a slot 31 of an arm 32. The arm 32 forms a part of the bell-crank lever 33 and each bell-crank lever is pivotally held in a bracket 34 extending upwardly from the base 13 or to a common pivot rod as preferred. The arm 35 of each bell-crank lever 33 is pivotally held by a knee or other joint at its outer end 36 to an upwardly extending link 37, and said link 37 at its upper end is pivoted at 39 to the short arm 40 of a type-bar 41. Each type-bar 41 is adapted to have a plurality of type or characters thereon according to whether 100 a single case shift or double case shift is employed. The type-bars are adapted to rest at their forward ends upon a felt, rubber or other cushion 42 and are arranged in a curved path within the type basket 43, said 105 type basket being suitably held in the main frame part of the machine in such a way that when a key-operated lever is moved on the depression of a key, the actuation of its coöperating bell-crank lever 33 will force a 110 link 37 downwardly and this will cause one of the type-bars to move the type upwardly and rearwardly to make an impression upon the work sheet about the platen 44 in the usual way. 115

As a means to lock the keys and the foldable parts of the key-operated levers to fold and unfold together, a bar 45 extends transversely of the machine over the parts 24 and under the parts 24 is a substantially 120 U-shaped rod 46. The rod 46 is pivotally mounted between the sides of the shallow frame part 15 and is adapted to be forced to the position shown in dotted lines in Fig. 2 so that the transversely extending portion 47 will lie directly under the parts 24 of the key-operated levers thus holding the parts 24 of said levers which fold between 125

the transversely extending bar 45 and the portion 47 and thereby prevent their disarrangement. The bar 45 may have a rubber or other strip forming an engaging surface 5 for the key-operated levers, and the rod 46 may have a knob or handle to move the same, it being understood that the key-lever parts 24 are not held so tight between the bars 46 and 47 as will prevent such relative 10 movement of the keyboard frame part 15 and the key-lever parts 24 as is necessary because of their different pivot points.

The platen 44 is mounted upon a platen carriage 48. This platen carriage 48 is 15 adapted to travel transversely of the machine on a foldable support 49. This support 49 has two members 50 and 51 which are hinged together at 52 at the upper portion of the machine. The support member 20 51 rests when in a normal operative position upon a transversely extending bar 53 forming a part of the vertically movable member 50 of the platen carriage support. The platen carriage may be variously constructed. 25 As shown it comprises end pieces or brackets 54 which extend upwardly from a carriage base 55 and said base may be held to travel transversely of a carriage bed. The carriage bed may extend rearward as far as 30 the hinge 51 or may be supported between foldable arms or in any other desired way. The carriage end pieces 54 support the axis or shaft 56 of the platen and said end pieces may also support a paper apron 57 in which 35 may be mounted a pressure or feed-roll 58, there being paper fingers and such other parts as are usually employed to hold and guide the work about the platen.

While the platen carriage with its bed 40 forming one member of the carriage support is adapted to fold rearwardly and downwardly so as to extend within the main frame part 11 and between the sides thereof when in a compact position as shown in 45 dotted lines in Fig. 2, the platen carriage and both members of the support are adapted to be shifted for upper case characters when in a normal operative position, though it will be understood that the platen carriage may have two shift movements instead of one, or the type basket itself may be shifted as in some forms of writing machines, if desired. The movable carriage support member 50 at each end has upright 50 portions 59 and these portions 59 have a tongue and groove or other connection with the sides of the main frame part 11 or otherwise held to move vertically thereon so that in its vertical movement the platen 60 carriage with its bed 54 will partake of such vertical movement. A pin or stud 60 projecting inwardly from each side of the main frame part 11 enters a slot 61 in each carriage support portion 59 and adapt-

ed to engage the lower edge of said portion 59 of the carriage support is an eccentric 62. There may be an eccentric on each side of the machine connected by a shaft 63 to adapt a uniform movement to be given to the carriage support without canting or twisting the same, and said shaft 63 is journaled in brackets 64 on the frame base 13. An arm 65 extends upwardly from the shaft 63 at each side of the machine and connected to each arm 65 is a link 66. Each 70 link 66 is connected to an arm 67 of a bell-crank lever which is mounted in the bracket 34 on the same rod as the bell-cranks 33 are mounted. A shift lever 68 is located at each side of the machine so that the platen carriage may be shifted from either side of the keyboard, and each shift lever comprises two parts 69 and 70, which have a knee joint connection similar to the key-operated levers 23 in order that said shift 85 levers may have one part fold relatively to the other part and the foldable part thereof movable as a part of the keyboard when the keyboard frame part is folded to its compact position. The parts 70 of the shift 90 levers are adapted to operate the bell-crank arms 67. These arms or either of them operate the links 66 and the eccentrics 62 on the depression of the shift keys, and this movement of the eccentrics 62 forces the carriage 95 support members 50 and 51 to place the printing point and the platen in position for writing upper case characters.

The platen carriage and its support may be held in its normal operative position 100 against relative backward folding movement in any desired way. As shown, a pin or stem 71, Figs. 3 and 8, has a knob or head 72 thereon and is normally forced inward by a spring 73. The pin 71 is adapted to 105 engage an aperture 74 in one end of the carriage bed or other part and lock said bed to the vertically moving supporting member 50 so that the platen carriage cannot fold rearwardly until the pin is released. 110 The platen carriage may also be held against a swinging or free movement when in its folded compact position by a releasable pin or part 74^a or otherwise, which is held to the frame of the machine and is adapted to 115 engage under a part of the foldable carriage supporting member 51 when in its compact position, as shown in Fig. 2.

As an escapement operating mechanism to control the letter-feed movement of the 120 platen carriage any suitable construction of such mechanism may be employed. As one form of mechanism a universal bar 75 is provided, which is adapted to overlie the inner ends of the key-operated levers 23. This universal bar extends transversely of the machine and has upwardly extending ends 76 which are guided in tubular posts 125

or guides 77. The universal bar is normally forced downwardly in the path of the key-levers 23 by springs 78. The universal bar has inwardly extending arms 79 and these 5 arms extend upwardly, as at 80, at opposite sides of the machine. At the upper ends of the parts 80 are heads or slides 81 and 82. These heads 81 and 82 are suitably guided at their upper ends by brackets 83 or otherwise, and said heads are adapted to engage 10 rollers 84 and 85 respectively, both of which are mounted upon a transversely movable rod 86. The rod 86 is suitably supported in the machine frame and is normally forced 15 against the action of the heads 81 and 82 by one or more springs 87. The heads 82 are each provided with a straight portion 88 forming a normal seat for the rolls 85 and a beveled or inclined part 88^a forming a 20 wedge-like actuating part on each head. Pivoted held to each head is a pawl or dog 89. The pawls 89 have their free ends normally forced outwardly beyond the heads to provide teeth 90, and each tooth is adapt- 25 ed to move inwardly within a recessed part of the head during the upward movement of the heads and rods 80 on the depression of the key-operated levers. A spring 91 tends normally to force each pawl 89 out- 30 wardly or permit the pawls to be moved inwardly during the upward movement of the heads. The upward movement of the heads will cause the rolls and rod 86 to move transversely of the machine to a point indicated 35 by the first dotted line of roll as at 91^a, Fig. 5. As the pawls 89 are forced above the rolls 84 and 85, owing to their being held to yield, they will not operate said rolls but immediately that the teeth of said pawls are 40 above said rolls the teeth or ends 90 thereof will engage the upper portion of the rolls, and during the downward movement of the universal bar and heads 82 an additional throw will be given to said rod 86 to the 45 point indicated by dotted roll 91^b, said pawls being each held against upward movement by means of a stop or part 92 located immediately above said pawls. Two lugs or projections 93 which are spaced apart and 50 project rearwardly from the transversely movable rod 86 are adapted to span an arm 94 of an escapement detent or arm 95. The detent 95 is pivoted at 96 and has a retaining tooth or dog 97 and a longer tooth or dog 98 which are adapted alternately to engage 55 the teeth of a rack 99 by reason of the reciprocatory movement of the rod 86. The dog 98 is released during the additional throw given the rod 86 by the pawls 89 and 60 this will place the dog 97 in engagement with the rack, said dog 97 being released on the return movement of the rod 86 and the universal bar. The rod 86 may be operated on the downward movement of the pawls 89

instead of partly on the upward movement 65 of the heads 81 and 82 thus avoiding any lost motion between the projections 93 and arm of the detent 95, in which case said heads do not move the rod 86 on their upward movement and the wedge portions are 70 dispensed with. The rack 99 is supported under the platen carriage and may be pivoted at one end, as at 100, to adapt the escapement rack to be released from the escapement dogs, as will be presently described. The platen carriage is normally under tension of a spring in a drum 101, mounted under the carriage supporting members to shift therewith and is adapted through the usual strap or connection to 75 move the carriage a letter space each time the universal bar is operated, though instead of the particular form of mechanism shown a limber and a fixed dog adapted alternately to engage the rack teeth, as is common in 80 many forms of typewriting machines, may be employed and operated by the rod 86 or in any other desired way. By having the universal bar actuate the reciprocating bar 86 on its downward movement rather than 85 its upward movement the letter feed movement of the carriage takes place at a time after the type have moved against the work on the platen; otherwise the carriage might move at or about the time an impression is 90 made by the type. The rod 86 may be made to reciprocate from right to left instead of left to right to release the escapement, in 95 which case the dog 97 will normally engage the rack. The heads 81 and 82 will in that 100 case be reversed.

It will be evident that the escapement dogs and rack which are both mounted upon the platen carriage support may by reason of the arm 94 resting between the projecting 105 lugs or parts 93 on the transversely extending rod 86 be separated therefrom when the platen carriage and its supporting bed are moved to a compact position, and on the platen carriage being restored to its normal operative position the arm 94 will automatically position itself between said lugs or projections 93 ready to be operated when the keys and universal bar are operated. 110

The carriage may be letter spaced without 115 printing in any suitable way. The space bar 102 is connected to levers 103. These levers 103 are divided into two parts, 104 and 105, and said two-part levers are mounted upon the transversely extending rod 26 120 and have a knee-joint connection similar to the key-operated levers 23, so that the space bar and the forward parts 103 of the two-part levers may fold as a part of the keyboard. The inner parts 105 of the key-operated levers simply actuate the universal bar and have no connection whatever 125 with any of the printing instrumentalities,

The ribbon holder 106, is located substantially centrally of the machine and is adapted to support a ribbon in position to cover the printing point on the platen 44. 5 The ribbon holder 106 is pivoted at 107 to a part of the main frame and on opposite sides of the holder, adjacent to its pivot 107, are springs 108 and 109. The spring 108 is secured to the foldable part of the carriage 10 supporting member 51 to fold therewith while the spring 109 is held to a fixed part. The spring 108 is of greater strength than the spring 109 so that when the spring 108 is in the position shown in Fig. 2 the holder 15 will be held against downward folding movement, but when the spring 108 is folded away from the holder 106 to the position shown in dotted lines in said figure the spring 109 will force the holder rearwardly 20 and downwardly on its pivot to a compact position. That is, the ribbon holder will fold over to a substantially horizontal position, carrying the ribbon held thereby and may be restored to its normal operative position 25 manually or otherwise when the platen carriage is restored to its normal operative position. The ribbon from the holder 106 passes about ribbon spools 110 and 111 mounted upon downwardly extending arms 30 112. The ribbon spools may be detachably held to permit the ribbons to be readily replaced and said ribbon spools may each be frictionally held to its support against too free movement by a spring 113 which may be in the form of a strip or as a disk as preferred. The ribbon spools may have a toothed disk portion or ratchet wheel 114 as a part thereof and adapted to engage the teeth of the ratchet wheels are pawls 115. 35 The pawls 115 are mounted upon inwardly extending arms 116, held to the vertical rods 80 so that during the reciprocation of the universal bar and parts 80 the pawls 115 will impart a rotary step-by-step movement to 40 the ribbon spools to wind the ribbon from one spool on to another. 45

While the drawing shows both pawls 115 in engagement with the teeth of the ratchet wheels of the ribbon spools only one pawl 50 is in engagement at a time, and these pawls may be moved to engagement or disengagement manually and independently or they may be moved simultaneously as is common in some forms of typewriting machines, 55 whereby one pawl is disengaged when the other pawl is engaged in order that the direction of feed of the ribbon may be reversed at will. The ribbon feed is thus operated simultaneously with the movement of the 60 means for tripping the escapement, the ribbon feed being actuated during one movement of the universal bar and the escapement mechanism during the return movement of said universal bar. The pawls 115

and the direction of teeth of ratchet disks 65 114 may be reversed to permit the spools to be rotated during the downward movement of the universal bar instead of the upward movement.

The carriage may be released to permit 70 the same to move freely along its bed. As one means a bell-crank lever 116 is pivotally held to one of the carriage end brackets 54. This lever 116 is pivoted at 117 and has one arm thereof formed as a finger portion 75 118. The other arm of said lever is slotted as at 119, to engage a pin 120 on the carriage rack. This pin 120 is slidably held in the carriage end bracket and is normally forced in one direction by a spring 121 arranged in 80 said slot, said rack, as before stated, being pivoted at one end thereof and at its end opposite the part engaged by the lever 116. As the lever 116 is depressed the rack will be shifted to one side and be released from 85 the teeth of the escapement dogs thus permitting the carriage to be moved freely in either direction along the carriage bed.

As a line-spacing means for the platen 44 a ratchet wheel 122 is provided on the platen shaft 56 at one end thereof. The teeth of the ratchet wheel are adapted to be engaged by a pawl 123. The pawl 123 is mounted upon a lever 124 which is pivotally held to the platen shaft 56 and is adapted to move 90 about said shaft independently thereof, and during such movement will cause the pawl 123 to engage the teeth of the ratchet wheel and rotate the platen 44. A segment 125 is held to or formed as an extension of one of 95 the carriage end brackets 54, and said segment is slotted as at 126, and in said slot is held an adjustable stop 127, as a bolt and nut. This stop 127 may be variously positioned in the segment 125 and controls the 100 distance the line-spacing lever 124 is adapted to move. By adjusting the stop 127 the pawl 123 may be made to move the ratchet a single space or two spaces or more, according to the distance the lever 124 is adapted 105 to be moved on its axis. The platen is thus adapted to be line spaced varying degrees.

The operation of the invention will be readily understood from the foregoing description when taken in connection with the 115 accompanying drawings. The parts being in the position shown in the drawings, it will be evident that if the keys 22 are operated the key-levers will be also operated and the inner portion of the key-levers will move the 120 bell-crank levers 33, links 37, and type-bars 41 to make an impression on the work sheet about the platen 44. During the movement of the key-operated levers the universal bar will be operated and the upward movement 125 of the universal bar with the parts 80 will actuate the ribbon feed mechanism on the upward movement thereof, and on the return

movement of the universal bar the escapement dogs will be tripped through the action of the heads 82 as already described. The platen carriage and its supporting members 5 may be given a vertical shift movement by means of either one of the shift keys, the carriage and its supporting means being restored to its normal position on the release of said keys by springs or otherwise. If the 10 machine is to be made compact for transportation, the retaining pins 71 may be released which will permit the foldable member of the carriage support and the platen carriage with the spring 108 to be folded rearwardly 15 and downwardly, as shown in dotted lines in Fig. 2, and the keyboard frame part 15 with the parts 24 of the key-operated levers, the space bar and the shift keys may be also moved to a compact position, as shown in 20 dotted lines in said figure.

In Fig. 9 the construction of the machine is substantially identical with that already described, except that the type basket, type-bars and part of the type-bar action is constructed in such a way that the type-bar basket may be moved below the upper surface of the frame, so that no part of the typewriter mechanism will extend above said surface when the machine is compact 25 and in its transporting condition. The construction is shown in Fig. 9 separately from that of the disclosure in Figs. 1 and 2 in order not to confuse the parts, and it is to be understood that this construction may be 30 embodied with the mechanism and parts shown in Fig. 2 or with any other suitable mechanism. As shown in this figure the type basket 128 is supported by uprights or standards 129 which have a pin-and-slot connection as 130 to adapt the type basket to 35 lower to the position shown in dotted lines. The type bar basket may be engaged when in a normal position by a latch or catch 131 which is normally pressed to an engaging 40 position by a spring 132, and which may be readily released by the operator so as to adapt the type basket to lower. The type-bar operating levers 132 are made in two 45 parts 133 and 134 which have an elbow or 50 knee joint as 135, to adapt the links to assume the position shown in dotted lines when the type basket is lowered. The joints between the parts 133 and 134 of the links 55 are such that when in the position shown in full lines a positive connection is made between the type-bars and the bell-crank levers 135, said levers 135 being operated by the key-operated levers in the same manner as already described.

60 From the foregoing it will be evident that a simple and efficient typewriting machine is provided wherein the keys forming a part of a universal keyboard and the platen carriage may be moved or folded to a more compact 65 position when not in use than when in a nor-

mal operative condition; that simple and efficient means are provided whereby the foldable part of the keyboard may be retained or locked against movement during such folded movement; that means are provided whereby the type basket may also be moved to a compact position; that simple and efficient ribbon mechanism is provided; that a separable escapement mechanism is provided whereby the platen carriage may 70 fold from a normal operative position to an inoperative and compact one and the connection with the escapement mechanism again effected without adjustment of parts; that simple case shift means is provided; and 75 that said machine is simple in construction and may be readily made and assembled.

Having thus described my invention, I claim as new and desire to secure by Letters Patent:—

1. In a typewriting machine, the combination of a main frame having a main frame part and a keyboard frame part hinged to move relatively from a normal operative position to a more compact one, a platen carriage, a support member on which the platen carriage is mounted and foldable from a normal operative position with said member rearwardly and downwardly to place the platen and carriage within the main frame part, a plurality of banks of keys forming a part of a universal keyboard movable with the keyboard frame part upwardly and rearwardly from an extended and normal operative position to a more compact one and 90 within the main frame part, type-bars mounted upon the main frame part and operatively connected to the keys, and means for locking the keys of the keyboard to the keyboard frame part. 95

2. In a typewriting machine, the combination of a main frame having a main frame part and a keyboard frame part hinged to move relatively from a normal operative position to a more compact one, a platen carriage, a support member on which the platen carriage is mounted and foldable from a normal operative position with said member rearwardly and downwardly to place the platen and carriage within the main frame part, a plurality of banks of keys forming a part of a universal keyboard movable with the keyboard frame part upwardly and rearwardly from an extended and normal operative position to a more 100 compact one, and type-bars mounted upon the main frame part and operatively connected to the keys. 110

3. In a typewriting machine, the combination of a main frame having a main frame part and a keyboard frame part hinged to move relatively from a normal operative position to a more compact one, a platen carriage foldable from a normal operative position rearwardly and downwardly to place the 115 120 125 130

platen and carriage within the main frame part, a plurality of banks of keys having a common hinge connection separate from the hinge of the keyboard frame part, and movable with the keyboard frame part upwardly and rearwardly from an extended and normal operative position to a more compact one within the main frame part, type-bars mounted upon the main frame part and operatively connected to the keys, and means for holding the keys of the keyboard to the keyboard frame part to fold and unfold therewith.

4. In a front-strike typewriting machine, the combination of a main frame having a main frame part and a keyboard frame part hinged to move relatively from a normal operative position to a more compact one, a platen carriage, a support member on which the platen carriage is mounted and foldable from a normal operative position with said support rearwardly and downwardly to place the platen and carriage within the main frame part, a plurality of banks of keys forming a universal keyboard movable with the keyboard frame part upwardly and rearwardly from an extended and normal operative position to a more compact one, two-part hinged levers on one part of which the keys are mounted to move with the keys and the keyboard frame part, type-bars mounted upon the main frame part and operatively connected to the keys, and means for holding the keys of the keyboard to the keyboard frame part to fold and unfold therewith.

5. In a typewriting machine, the combination of a main frame having a main frame part and a keyboard frame part hinged to move relatively from a normal operative position to a more compact one, a platen carriage foldable from a normal operative position rearwardly and downwardly to a more compact position, a plurality of banks of keys forming a part of a universal keyboard movable with the keyboard frame part upwardly and rearwardly from an extended and normal operative position to a more compact one, and type mounted upon the main frame part and operatively connected to the keys.

6. In a typewriting machine, the combination of a main frame part, type-bars, a platen carriage mounted to travel transversely of said frame part and foldable rearwardly and downwardly out of the path of the type-bars within the main frame part, and a plurality of banks of keys forming a part of a keyboard foldable upwardly and rearwardly within the main frame part in front of the type-bars.

7. In a typewriting machine, the combination of a main frame part, type, keys for operating the type, a platen, a platen carriage, and a support for the platen carriage

pivotaly connected adjacent its rear edge with the main frame part and movable rearwardly and downwardly to swing the carriage and platen from normal operative position into an inoperative compact position 70 within the rear portion of the main frame part.

8. In a typewriting machine, the combination of a main frame, a keyboard frame part connected to the main frame and movable from an extended operative position to an inoperative compact position within the main frame, a plurality of banks of keys forming part of a universal keyboard movable with said keyboard frame part within 80 the main frame, type mounted on the main frame and operatively connected with the keys, platen-supporting means mounted on the main frame and movable from a normal operative position rearwardly and downwardly within the main frame, a platen shift key movable with the keyboard frame part, means on the main frame operatively connected with said shift key for shifting the platen-supporting means to print different 90 case characters, ribbon feeding means mounted on the main frame, and a ribbon holder mounted on the main frame and movable from a normal operative position to a compact inoperative position. 95

9. In a typewriting machine, the combination of a main frame part, a platen carriage, type, and a plurality of banks of keys forming a part of a keyboard and movable from a normal operative position to a 100 more compact one in front of the type and within said frame part.

10. In a typewriting machine, the combination of a main frame part, a platen carriage, type, and a plurality of banks of 105 keys operatively connected to the type and foldable toward the type from a normal operative position to a more compact one within said frame part while maintaining the connection with said type. 110

11. In a typewriting machine, the combination of a main frame part, a platen carriage, type-bars, a ribbon holder, and a plurality of banks of keys forming a part 115 of a keyboard all mounted on the main frame part and all foldable from a normal operative position to a more compact one.

12. In a typewriting machine, the combination of a main frame part, a platen carriage, type-bars, a ribbon holder, and a 120 plurality of banks of keys forming a part of a universal keyboard all mounted on the main frame part, and all foldable independently and in different directions from a normal operative position to a more compact one. 125

13. In a front-strike typewriting machine, the combination of a main frame having a main frame part, a platen carriage, a support for said platen carriage movable with 130

the platen carriage from a normal position rearwardly and downwardly to a more compact one, a plurality of banks of keys forming a part of the universal keyboard and 5 movable from a normal operative position to a more compact one, type-bars operatively connected to the keys, and a type-bar basket forming a support for the type-bars and movable bodily from a normal operative 10 position to a more compact one and in a direction different from that of the compact movement of the keys and the platen carriage.

14. In a front-strike typewriting machine, 15 the combination of a main frame, a platen carriage, a plurality of banks of keys forming a part of a keyboard, type-bars operatively connected to the keys, and a type-bar basket forming a support for the type-bars 20 and movable from a normal operative position to a more compact one.

15. In a typewriting machine, the combination of a main frame, a platen carriage, a support for said platen carriage movable 25 with the platen carriage from an abnormal position rearwardly and downwardly to a more compact one, a plurality of banks of keys forming a part of a keyboard, type-bars operatively connected to the keys, and 30 a type-bar basket forming a support for the type-bars and movable from a normal operative position to a more compact one and in a direction different from that of the compact movement of the platen carriage.

16. In a front-strike typewriting machine, 35 the combination of a main frame, a platen carriage, a support for said platen carriage, a plurality of banks of keys forming a part of the universal keyboard and foldable upwardly from a normal operative position 40 to a more compact one, type-bars operatively connected to the keys, and a type-bar basket forming a support for the type-bars and movable bodily from a normal operative position to a more compact one and in a direction 45 different from that of the compact movement of the keys.

17. In a typewriting machine, the combination of a main frame part, a foldable keyboard, a foldable platen carriage, type 50 operatively connected to the keyboard, and a type-basket bodily movable from a normal operative position to a more compact one.

18. In a typewriting machine, the combination of a main frame part, a keyboard, a 55 platen carriage, and type-bars operatively connected to the keyboard and bodily movable from a normal operative position to a more compact one.

19. In a typewriting machine, the combination of a main frame part, a foldable platen carriage, means for locking the platen carriage in its normal position against folding movement, a retainer for holding the 60 platen carriage in its folded position, a key- 65

board, printing instrumentalities operated by said keyboard, means whereby the keys of the key-board may fold to a compact position and unfold, and means for locking the keys to move in unison during such folding and unfolding. 70

20. In a typewriting machine, the combination of a main frame part, a platen carriage, a keyboard, printing instrumentalities operated by said keyboard, means whereby the keys of the keyboard may fold to a compact position and unfold, and means for locking the keys to move in unison during such folding and unfolding movement. 75

21. In a typewriting machine, the combination of a main frame, a platen carriage foldable rearwardly and downwardly thereon, type, key-operated levers operatively connected to said type, said key-operated levers comprising two parts having a common axis, one part of each lever being foldable with relation to the other and the folding movement being upwardly and rearwardly. 80

22. In a typewriting machine, the combination of a main frame part, a platen carriage foldable rearwardly and downwardly and within the main frame part, type, key levers operatively connected to said type, means to permit said key levers to fold upwardly within the main frame part, and means to hold said key levers in their folded position. 85

23. In a typewriting machine, the combination of a rigid main frame part, a platen carriage, means for supporting said platen carriage and adapted to be folded rearwardly and downwardly within the main frame part, a keyboard pivoted at the forward edge of the main frame, means to permit said keyboard to be folded upwardly into the main frame part, and means for holding said keyboard in its folded position. 90

24. In a typewriting machine, the combination of a rigid main frame part, a platen carriage, means for supporting said platen carriage and adapted to be folded rearwardly and downwardly within the main frame part, a keyboard pivoted at the forward edge of the main frame, means to permit said keyboard to be folded upwardly into the main frame part, means for holding said keyboard in its folded position, a type segment, and a ribbon mechanism in the main frame part between the platen carriage and the keyboard. 110

25. In a typewriting machine, the combination of a rigid main frame part, a platen carriage, means for supporting said platen carriage and adapted to be folded rearwardly and downwardly within the main frame part, a keyboard pivoted at the forward edge of the main frame, means to permit said keyboard to be folded upwardly into the main frame part, means for holding said keyboard in its folded position, a key- 115 segment, and a ribbon mechanism in the main frame part between the platen carriage and the keyboard. 120

125

- keyboard in its folded position, a type segment, and a ribbon mechanism supported by and within the main frame part between the platen carriage and the keyboard.
26. In a typewriting machine, the combination of a main frame part, a platen carriage, a keyboard frame part hinged to the main frame part, springs adapted to hold the keyboard frame part in either of two positions, a plurality of banks of keys forming a part of the keyboard and foldable with the keyboard frame part, and means mounted upon the keyboard frame part for locking the keys thereto during the folding and unfolding movement thereof. 70
27. In a typewriting machine, the combination of a main frame part, a platen carriage, a keyboard frame part hinged to the main frame part, springs adapted to hold the keyboard frame part in either of two positions, nuts located at the hinge for holding the frame parts against folding movement, a plurality of banks of keys forming a part of the keyboard and foldable with the keyboard frame part, and means mounted upon the keyboard frame part for locking the keys thereto during the folding and unfolding movement thereof. 75
28. In a typewriting machine, the combination of a main frame, a platen carriage, a ribbon holder, a plurality of banks of keys forming part of a keyboard, said carriage and ribbon holder and keys being mounted on the main frame and independently movable from a normal operative position to a more compact position, and type bars mounted on the main frame and adapted to be actuated by said keys. 80
29. In a typewriting machine, the combination of a main frame, a keyboard connected with said frame and movable from an extended operative position into an abnormal compact position, a platen carriage supported on the main frame and movable from a normal operative position to an abnormal compact position, a type basket supported on the main frame and bodily movable independently of the platen carriage and keyboard from a normal operative position to a more compact one, and type bars mounted in said type basket and adapted to be actuated by said keyboard. 85
30. In a typewriting machine, the combination of a main frame part, a platen carriage, a keyboard frame part pivotally connected to the main frame part and movable from an extended operative position to an abnormal compact position, a plurality of banks of keys forming part of a keyboard and movable with said keyboard frame part from normal extended position to an abnormal compact position, and means carried by the main frame part for holding the keyboard frame part in its extended and compact positions. 90
31. In a typewriting machine, the combination of a main frame, a platen carriage supported on the main frame and adapted to swing from a normal operative position rearwardly and downwardly into the rear portion of the main frame, a keyboard foldable from an extended operative position to a compact position within the forward portion of the main frame, a type basket normally supported in an elevated position in the main frame and movable downwardly into a compact inoperative position within said frame, and type bars mounted in said type basket adapted to be operated by said keyboard. 95
32. In a typewriting machine, the combination of a main frame, a platen carriage supported on the main frame and adapted to swing from a normal operative position rearwardly and downwardly into the rear portion of the main frame, a keyboard foldable from an extended operative position to a compact position within the forward portion of the main frame, a type basket normally supported in an elevated position in the main frame and movable downwardly into a compact inoperative position within said frame, type bars mounted in said type basket, and constantly maintained foldable operating connections between the type bars and keyboard. 100
33. In a collapsible typewriting machine, the combination of a frame, a platen, a support for the platen, connections between said support and the frame whereby the platen may be moved from a normal operative position to an inoperative position in more compact relation with the frame, and a ribbon holder hinged to the frame independently of the platen support and foldable relatively to the frame and platen support from a normal upwardly extending operative position to a substantially horizontal inoperative position in close relation with the platen when the platen is in its inoperative position. 105
34. In a collapsible typewriting machine, the combination of a frame, a platen, a support for the platen, connections between said support and the frame whereby the platen may be moved from a normal operative position to an inoperative position in more compact relation with the frame, ribbon spools mounted on the frame independently of the platen support, and a ribbon holder pivotally held to the frame independently of the platen support and foldable about its pivot relatively to the spools and platen support from a normal upwardly extending operative position to a lower inoperative position in close relation with the platen when the platen is in its compact inoperative position. 110
35. In a typewriting machine, the combination of a frame, a platen supported on 115

the frame and foldable rearwardly and downwardly from a normal elevated operative position to a lower inoperative position, ribbon spools and mechanism for rotating the same mounted in the frame, and a ribbon holder supported in the frame and foldable rearwardly and downwardly relatively to the platen and the ribbon spools from an upwardly extended operative position to an inoperative position in more compact relation with the frame and above the platen when the platen is in its lower inoperative position.

36. In a typewriting machine, the combination of a frame, a platen carriage support, a platen carriage mounted on the support and movable therewith from a normal elevated operative position into a more compact position within the rear portion of the frame, and a ribbon holder pivotally supported in the frame at a point in front of the platen carriage support, said ribbon holder being adapted to be swung rearwardly and downwardly from an extended operative position into compact relation with the frame after the platen carriage has been moved into its compact position.

37. In a typewriting machine, the combination of a frame, a platen carriage supported on the frame and movable from a normal operative position into a more compact position, a ribbon holder supported in the frame and movable relatively to the frame and the carriage from an extended operative position into more compact relation with the frame, and means for automatically moving the ribbon holder to compact position when the platen carriage is moved to compact position.

40 38. In a typewriting machine, the combination of a frame, a platen carriage supported on the frame and foldable rearwardly and downwardly from a normal operative position to a more compact position, a ribbon holder pivotally held to a stationary part of the machine and adapted to swing rearwardly and downwardly from a normal operative position to a more compact position, a spring partaking of the folding movement of the carriage adapted to hold the ribbon holder in its extended operative position, and a spring of less tension than the first mentioned spring, supported in a fixed position in the frame and tending normally to force the ribbon holder to its compact position.

39. In a typewriting machine, the combination of a frame, a platen carriage supported on the frame and foldable from a normal operative position to a more compact position, and a ribbon holder pivotally held to a fixed part of the machine and foldable from a normal operative position to a more compact position subsequently to the folding movement of the platen carriage.

40. In a typewriting machine, the combination of a frame, a platen carriage supported on the frame and foldable from a normal operative position rearwardly and downwardly to a more compact position, ribbon spools supported in the frame in fixed relation thereto, and a ribbon holder pivotally mounted in the frame and foldable relatively to the spools rearwardly and downwardly from a normal operative position to a more compact inoperative position.

41. In a typewriting machine, the combination of a frame, a platen carriage supported in the frame and foldable from a normal operative position to a more compact position, a ribbon holder pivotally held to a part of the machine and foldable relatively to the carriage to a compact inoperative position, and means partaking of the folding movement of the carriage adapted to hold the ribbon holder in its operative position.

42. In a typewriting machine, the combination of a frame, a platen carriage supported in the frame and movable from a normal operative position to a more compact inoperative position, a ribbon holder supported in the frame and movable relatively to the platen carriage from an extended operative position into a more compact inoperative position, means for automatically moving the ribbon holder to compact position when the platen carriage is moved to compact position, and means partaking of the compacting movement of the carriage for holding the ribbon holder in its normal operative position when the carriage is in its normal operative position.

43. In a typewriting machine, the combination of a frame, a platen foldable from a normal elevated operative position to a lower and more compact position within the frame, and a ribbon holder held to a fixed part of the frame and foldable rearwardly and downwardly from a normal operative position to a more compact position above the platen when the platen is in its compacted position.

44. In a typewriting machine, the combination of a frame, a platen foldable from a normal elevated operative position to a more compact lower position within the frame, ribbon spools held to the frame, and a ribbon holder pivotally held to the frame and foldable relatively to the ribbon spools rearwardly and downwardly to a point above the platen when the platen is moved to compact position.

45. In a collapsible typewriting machine, the combination of a main frame, a platen, means for supporting the platen in an elevated operative position, connections between the platen supporting means and the frame whereby the platen may be moved from its elevated operative position to a

lower inoperative position within the rear part of the frame, type bars, a movable support for the type bars, connections between said type bar support and the frame where-
5 by said support and the type bars may be moved from a normal elevated operative position to a more compact inoperative position within the frame, and a keyboard op-

eratively connected with the type bars and foldable from a normal extended operative 10 position upwardly and rearwardly within the frame in front of the type bars.

This specification signed this 2d day of March, A. D. 1916.

PHILIPPE DE CLAMECY.
